UNITED STATES PATENT OFFICE.

AUGUST H. MILLER, OF CLEVELAND, OHIO.

METALLIC MONUMENT.

SPECIFICATION forming part of Letters Patent No. 364,661, dated June 14, 1887.

Application filed January 13, 1887. Serial No. 214,310. (No model.)

To all whom it may concern:

Be it known that I, AUGUST H. MILLER, a citizen of the United States, residing at Cleveland, in the county of Cuyahoga and State of Ohio, have invented certain new and useful Improvements in Metallic Monuments; and I do hereby declare that the following is a full, clear, and exact description of the invention, which will enable others skilled in the art to 10 to which it appertains to make and use the same.

My invention relates to metallic monuments, and is an improvement on the construction patented to me under date of November 9, 1886, No. 352,422. In said patent I show a 15 monument built in sections, connected in the center by means of a single rod, extending from top to bottom thereof, said sections composed of a series of separate plates connected together by tongue-and-groove joints, and having on their inner faces projecting lugs with inclined brace-bars connecting the plates and caps, as therein shown. In the present case I form the central rod in sections, and by using a nut at each joint of the rod am enabled to 20 tie down each section as it is erected, as well as afterward to tighten the section as they may need it. Another advantage of this construction is that it enables me to loosen the sections separately at any point when for any 25 reason this becomes desirable.

Another improvement in construction is found in the manner of connecting the plates of the respective sections, which in this instance consists in lugs and notches in the meeting edges of the respective sections.

Another improvement is found in the means for locking the panels in position on the plates.

These consist in a central vertical locking-bar and a pair of cross bars or arms, all of 40 which bear against the panel, and are fastened to the plates, as hereinafter described.

Another important improvement is in the manner of connecting the central rod with the base stone of the monument. These and other 45 improvements and combinations of parts, as shown and described, and more particularly pointed out in the claims, constitute my invention.

Referring to the drawings, Figure 1 is a vertical elevation of a monument constructed according to my invention. Fig. 2 is a vertical

elevation of the monument, partly broken away to disclose the connecting-rod and other features of construction connected therewith. Fig. 3 is a detail of one of the several plates 55 forming the respective sections, with the locking device for the panel in position on its inner side. Fig. 4 is a separate view of the said locking device. Fig. 5 is a detail of the cap which mounts the respective and upon which 60 the next succeeding section rests. Fig. 6 is a separate view of the locking-nut with a section of the connecting-rod attached, and Fig. 7 a section thereof. Fig. 8 is an enlarged section of one of the section-plates shown in Fig. 3. 65 Fig. 9 is an enlarged view of the ball-socket at the top of the monument.

It will be understood that the entire structure herein described, excepting in some instances the panels, is formed of metal, and 70 preferably of cast metal, though, of course, other material, if any is found sufficiently durable and has the quality to be molded, may be adopted without departing from the invention.

The pedestal or base A, as here shown, consists of stone, and is provided with a rectangular recess, a, in the center for fastening the connecting-rod. This recess is formed with two of its sides converging slightly from the 80 bottom to the top of the recess. In this recess I place a block, a', having four straight sides, corresponding to the sides of the recess, and of such size at its base as to just freely pass through the top of the recess. Then when the 85 block is inserted a free space is left at one side, and, this being filled with a key or wedge, a'', the block is firmly locked in the recess. A screw-threaded opening, a'', serves for fastening the connecting-rod B. The rod B is formed 90 in sections b, one corresponding to each section of the monument, and having a coupling-nut, b', preferably cast thereon, so as to avoid threading, except at one end. This enables me to tighten the respective sections upon the 95 base and upon each other as I go in the erection of the monument, as well as to make the rod convenient for packing and shipping, which is of much importance to me.

C represents one of the four plates constituting the respective sections of the monument. These plates are made larger or smaller, ac-

according to the size of the monument, and are constructed alike in all particulars. As shown in Figs. 3 and 8, the plate is provided with a central opening, c , over which the panel is placed upon the inside. Each plate has a curved extention, c' , on one side, the base of which at c' extends outward beyond the face thereof and curves thence around toward the rear of the plate, furnishing a plain straight to inside surface, c'' .

Inside of the curved extention are two lugs, c , having notches c^1 , adapted to engage and lock the adjoining plate, which stands at right angles to the plate here described and has its edge formed as shown at the right of Figs. 3 and 8. At this edge are two slight lugs, c' , which set in the notches c^1 , and when dressed down to suitable size make a close joint between the meeting edges of the two plates. The tongue and groove joint shown in my former patent was found inconvenient and troublesome when it came to setting up the monument, as in some instances the entire length of a plate had to be dressed to get the desired connection; but by employing the lugs and notches here described the work of fitting can be easily and quickly done.

D represents a section cap, which may be cast in a single piece or in two horizontal sections, d d' , as shown in the middle of Fig. 2. On the bottom of the said cap is a bead or its equivalent for engaging and holding the top ends of the side pieces, and beads d^2 on the top of the caps are provided for a like purpose. The precise means of making these connections is not deemed material, provided the parts are so united that they will interlock and be firmly secured.

d d' represent cross-braces with a central socket, d^1 , in which the small end of the lock-nut upon the connecting-rod rests, and is free to turn when the sections are tightened together.

E is a front view of one of the panels, which is held in position on the inside of the plate by lugs e at the sides and slotted posts e' e^2 at the top, within which it fits, and cross arms F. (Shown separately in Fig. 4.) These arms bear upon the panels at their ends, and are locked in position by the longitudinal arm f, which has a beveled head, f' , at its lower end, resting in a slot in the post e' , and a tapering upper end extending through a corresponding slot in the upper lug, e^2 . By inserting the cross-arms, as shown in Fig. 3, and driving a wedge into the upper slot, e^2 , behind the arm f, the several arms will bear against the panels and hold them firmly in position.

G represents the crown-cap, which corresponds in general make-up and function to the

locking-nut, and rests in a flanged socket in the neck of the finishing section H. This cap is the last thing put in place, and when screwed down the erection of the monument is complete, and all the parts are not only firmly united and locked from removal from the outside, but the monument to all appearance is as solid as marble or granite, which it may be made to resemble.

It will of course be understood that the exact details of construction herein set forth need not be followed where other and equivalent means will answer the same purpose.

Having thus described my invention, what I claim, and desire to secure by Letters Patent, is—

1. A monument built in sections one upon the other and a sectional connecting-rod provided with nuts at the respective joints of the rod, which bear upon the section below, and are threaded to secure the end of the next succeeding joint of the rod above, whereby each section of the monument as erected may be fastened down, substantially as set forth.

2. A sectional monument, each section having a cap-piece provided with a socket in the center, in combination with a sectional connecting-rod and a lock-nut therefor to lock the rod on the cap-piece, and thereby tighten the section it surmounts, substantially as set forth.

3. A sectional monument, each section of which is composed of separate plates locked together by lugs, and having cap-pieces with central sockets, in combination with a connecting-rod made in sections corresponding to the sections of the monument, and a nut to both secure the respective sections of the monument and the sections of connecting-rod together, substantially as set forth.

4. In a sectional monument, the section-plates provided with central openings and slotted lugs on the inside, in combination with panels to cover the openings and cross-arms to fasten the panels, the vertical arms having a beveled head at one end and tapered at the other end to enter said slots and lock the panels, substantially as described.

5. In a monument, a base or pedestal having a recess provided with sides converging toward the top thereof, in combination with a block formed with corresponding sides and adapted to be locked in said recess, said block having an opening for attaching the connecting-rod, substantially as set forth.

AUGUST H. MILLER.
